[57] **CLAIM**

The ornamental design for a portable computer, as shown and described.

DESCRIPTION

FIG. 1 is a top, front left side perspective view of the portable computer in a closed position showing my new design;

FIG. 2 is a top, front, left side perspective view thereof, the computer in an opened position;

FIG. 3 is a left end elevational view thereof, on an enlarged scale;

FIG. 4 is a right end elevational view thereof, on an enlarged scale, the computer in a closed position;

FIG. 5 is a right end elevational view thereof, on an enlarged scale, the computer in the opened position;

FIG. 6 is a rear elevational view thereof, on an enlarged scale, the computer in the closed position;

FIG. 7 is a bottom plan view thereof, on an enlarged scale;

FIG. 8 is a top plan view thereof on an enlarged scale, the computer in the closed position;

FIG. 9 is a front elevational view thereof on an enlarged scale, the computer in the closed position;

FIG. 10 is a top plan view thereof on an enlarged scale, and the computer in the open position; and

FIG. 11 is a front elevational view thereof on an enlarged scale, the computer in the opened position.

FIG.1.

FIG.2.

FIG. 3.
